(57) **CLAIM**

The ornamental design for an adapter sleeve for a vise block, as shown and described.

DESCRIPTION

FIG. 1 is a perspective front view of an adapter sleeve for a vise block showing my new design;

FIG. 2 is a front view of the adapter sleeve;

FIG. 3 is a right side view of the adapter sleeve;

FIG. 4 is a rear view of the adapter sleeve;

FIG. 5 is a left side view of the adapter sleeve;

FIG. 6 is a top view of the adapter sleeve;

FIG. 7 is a bottom view of the adapter sleeve;

FIG. 8 is a rear perspective view of the adapter sleeve;

FIG. 9 is a bottom perspective view of the adapter sleeve;

FIG. 10 is a front perspective view of the adapter sleeve on a vise block;

FIG. 11 is a front perspective view of the adapter sleeve in relation to a vise block; and,

FIG. 12 is a rear perspective view of the adapter sleeve on a vise block.

The broken lines of the adapter sleeve depict parts of the adapter sleeve that form no part of the claimed design. The broken lines of the vise block depict the environment and form no part of the claimed design.

1 Claim, 9 Drawing Sheets
